US00D855807S

(12) **United States Design Patent** (10) **Patent No.:** **US D855,807 S**
(45) **Date of Patent:** **** Aug. 6, 2019**

(54) **EXTERNAL PULSE GENERATOR**

(71) Applicant: **Axonics Modulation Technologies, Inc.**, Irvine, CA (US)

(72) Inventor: **Dennis Lynn Schroeder**, Irvine, CA (US)

(73) Assignee: **AXONICS MODULATION TECHNOLOGIES, INC.**, Irvine, CA (US)

(**) Term: **15 Years**

(21) Appl. No.: **29/603,422**

(22) Filed: **May 9, 2017**

(51) LOC (12) Cl. **24-01**

(52) U.S. Cl.

USPC **D24/167**

(57) **CLAIM**

The ornamental design for an external pulse generator, as shown and described.

DESCRIPTION

FIG. 1 is a front perspective view of the external pulse generator showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate features of the external pulse generator that form no part of the claimed design.
